UNITED STATES PATENT OFFICE

JOHN W. SHAW, OF NORWOOD, NEW JERSEY

AWNING-OPERATING MECHANISM

Application filed April 23, 1928. Serial No. 272,075.

The present invention is concerned with awning operating mechanism which may have a wide range of utility but which is peculiarly adapted for use in connection with 5 window awnings where it is desired to manipulate the awning from within a room without opening the window.

The mechanism is applicable to various styles of awnings, such for instance as the 10 drop type although it is primarily intended for association with the roller type awnings now commonly employed. The mechanism is also conveniently applicable to various styles of windows and casements regardless 15 of whether sliding sashes or swinging sashes are mounted in such casements. It may be applied to various standard windows with no need for altering the awning and with but slight changes in the window construction. In fact the only alteration needed in 20 the window construction is the provision of openings in the sash or frame to permit the passage of a flexible operating device from the inside to the outside of a window.

25 An object of the invention is to provide operating mechanism so designed that a woman or a child may readily manipulate, without physical exertion, even a heavy awning such as may be employed with a wide metal fixed sash type of window.

Another object is to provide a mechanism which will be inconspicuous and which will not detract from the usual neat appearance of either the inside or outside of a window.

35 Another object is to provide an awning manipulating mechanism in which no springs are required and none of the moving parts of the mechanism are fragile or likely to get out of order.

40 A further object is to so arrange and assemble the important parts of the mechanism that they may be attached to and removed from a window with expedition and facility and all parts are readily accessible for purposes of repair or replacement.

45 Additional objects are to provide mechanism utilizing parts which are devoid of sharp corners or protruding edges likely to 50 tear the awning and which will aid in pre-

venting the awning from becoming creased or jammed on its roller.

Further and more general objects are to provide a mechanism of simple practical construction which will be rugged, durable 55 and efficient in use and well suited to the requirements of economical manufacture.

With the above noted and other objects in view the invention consists in certain novel features of construction and combinations and arrangements of parts which will be more fully hereinafter described and pointed out in the claims.

The invention may be more fully understood from the following description in connection with the accompanying drawings 65 wherein:

Fig. 1 is a perspective view of the exterior of a window showing an awning and associated operating mechanism applied to 70 the window, the awning being shown partially unrolled.

Fig. 2 is an enlarged broken vertical sectional view taken approximately on the line 75 2-2 of Fig. 1.

Fig. 3 is an enlarged fragmentary outside view with parts broken away and in section for the sake of clearness.

Fig. 4 is an enlarged broken sectional plan view taken on the line 4-4 of Fig. 5. 80

Fig. 5 is a vertical sectional view through the gear train taken on the line 5-5 of Fig. 4.

Fig. 6 is a perspective view of the awning roller.

Fig. 7 is an inside perspective view showing the sprocket chain keeper, and 85

Fig. 8 is an enlarged vertical sectional view through the chain operating sleeve.

In the drawings I have shown a metal window frame 10 within which is set a stationary 90 sash 11, the frame of which is provided with a center upright 12 through which the flexible operating device 13 is led.

The awning 14 is wound on a springless roller 15 mounted in brackets 16, 17 secured 95 to the window frame at opposite sides of the latter. These brackets are arranged to support the roller 15 outwardly beyond the brackets 18 which are secured lower down on opposite sides of the frame 10 and provide 100

pivotal mounting for the lower ends of the rigid arms 19, the upper ends of which are integrally connected by a cross piece 20 run through a hem in the awning adjacent the free edge of the latter.

Inasmuch as the pivots 21 for these arms are arranged inwardly of the rolled awning the cross piece 20 strikes the roll before the arms 19 can be swung to a vertical or dead center position. Thus the weight of these arms always acts to unroll the awning and move it toward its fully extended operative position.

The roller 15 is preferably a hollow metal tube having a plug 22 in one end thereof carrying a gudgeon 23 adapted to be dropped into a slot 24 in the bracket 16. The plug may be pinned in the hollow roller by a screw 24^a.

Bracket 16 includes the plate portion 16^a disposed in a vertical plane and projecting outwardly from the window frame and the integral horizontal plate portion 16^b secured against the underface of the top of the window frame.

The other roller supporting bracket 17 includes an attaching plate portion 17^b lying against the top of the window frame and a pair of spaced forwardly projecting parallel plates 17^a integrally connected at their ends and providing mountings for a train of intermeshing operating gears 25, 26, 27. Gear 27, the driven gear of the train, is preferably the largest one and its axle 28 projects well inwardly and mounts a hub 29 for the open end of roller 15. This roller at its open end is provided with diametrically opposed notches 30 receiving the radially projecting ends of a pin 31 passed through the hub 29 and holding this hub in place on the axle 28. The slot and pin connection 30, 31, couples the roller 15 and hub 29 for unitary rotary movement. It also permits the roller 15 to be readily emplaced and removed, removal being accomplished by merely lifting the gudgeon 23 out of its notch 24 and withdrawing the roller endwise from the hub 29.

The driving gear 25 which imparts movement to the driven gear 27 through a small idler 26 is also provided with an extended axle 32 mounting a hub 33 corresponding to the hub 29 and provided with a pin 34 similar to the pin 31.

The hollow horizontal driving shaft 35 is mounted between the roller 15 and the sash 11 in substantial parallelism with the roller. One end of the shaft is notched at 36 to slip over the hub 33 and engage the ends of pin 34. A plug 37 is secured by screw 37^a in the opposite end of shaft 35 and carries a gudgeon 38 mounted in the depending portion 39^a of a bracket 39 fixed to the top of the window frame at approximately the center thereof. A sprocket wheel 40 is held on the outer end of the gudgeon 38 by pin 41.

The endless flexible device 13 (in this case a sprocket chain) for rotating the wheel 40 passes from this wheel through an adjacent opening 42 in the upright 12, over the sprocket 43, mounted in a bracket 43^a secured to the inside of the upright 12. The sprocket chain extends downward within the room near the lower end of the window around sprocket 44 and out through the opening 45 over sprocket 46 and back to wheel 40. The sprockets 44, 46 are carried in brackets 44^a, 46^a secured respectively to the inner and the outer face of the bar 12 adjacent opening 45.

In order to prevent soiling or injuring the hands by contact with the sprocket chain, an operating sleeve 47 is mounted on the inner run of the chain between the sprockets 43, 44. This sleeve includes hollow spools 48 at its ends having annular grooves 49 therein, within which the ends of tubular inner and outer flexible concentric sleeves 50, 51 are secured. Sleeve 50 is preferably of leather or some similar tough long-wearing material adapted to withstand frequent frictional engagement with the chain, while sleeve 51 may be of velvet or other soft material which will serve as a cushion and grip for the hand and at the same time present an ornamental appearance.

The operation of the device is substantially as follows: To shift the chain in a direction to unroll the awning, the sleeve 47 is grasped tightly and raised, carrying the chain 13 with it. The sleeve is then released and slid down to its normal position after which the operation is repeated as many times as necessary. A reverse operation is of course resorted to in rolling up the awning; that is to say the sleeve is slid up on the chain and then it is grasped and pulled down carrying the chain with it.

In this operation the sleeve 47, which is normally capable of sliding freely on the chain, moves with the chain only because it is frictionally engaged therewith by the pressure of an operator's hand. It will be understood, of course, that the movement of the sprocket chain turns the shaft 35 and through the gears 25, 26, 27 rotates the awning roller 15 to positively roll up the awning or to permit the awning to unwind under the influence of the weight of the bar 20 and its arms 19.

Due to the powerful leverage afforded by the sprocket chain and gear train, raising or lowering of the awning requires the application of only a slight physical force and may be readily accomplished by a woman or a child.

In this connection, it will be noticed that practically no power is required to lower the awning other than an upward pull on the chain sufficient to overcome the frictional resistance of the sprocket chains and operating gear train. In raising or rolling up

the awning, however, particularly where the awning is a very wide, heavy one, some physical exertion is necessary, even with the powerful leverage, which the present mechanism affords. Since the manually applied force incidental to raising the awning may be more conveniently placed on the sprocket chain by a downward pull than by an upward lift, I employ the small reversing idler gear 26 in the gear train. By virtue of this arrangement, the person operating the awning may conveniently utilize their entire weight, if desired, to pull down on the chain, whereas the application of an upward lift on the chain cannot be aided by the weight of the body.

The friction of the gear train and the sprocket chain is ordinarily sufficient to balance the weight of the arms 19 and cross piece 20, so that the awning is retained against unrolling from any position of adjustment. If desired however, an additional positive safeguard may be provided to secure the chain against moving. This means may conveniently comprise a chain keeper fixed to the inner face of the bar 12. This keeper includes an attaching plate portion 52 screwed or otherwise secured as at 53 to the bar 12 and at its upper edge provided with a horizontal extension 54 having a keeper slot 55 extending inwardly from one edge thereof. The sprocket chain as seen in Fig. 7 is of conventional light wire construction. When the inner run of the chain is flexed inwardly and the intermediate portion of a chain link engaged in the slot 55 the chain will be securely held since the eyes or enlarged ends of the links cannot be pulled through the slot.

By so arranging the mechanism that the sprocket chain runs through the center frame bar 12, I eliminate any possible interference of the chain with curtains or draperies such as are commonly employed at the sides of the window.

Obviously the operating gear might with slight variations be applied to a drop type awning. Patently also the particular arrangement for gravitationally lowering the free edge of the awning is subject to change and other types of roller awnings, or analogous devices whether connected to pivoted arms or not might be manipulated by the present gear.

It will thus be seen that there is herein described a device in which the several features of this invention are embodied, and which device in its action attains the various objects of the invention and is well suited to meet the requirements of practical use.

As many changes could be made in the above construction, and many apparently widely different embodiments of this invention could be made without departing from the scope thereof, it is intended that all matter contained in the above description or

shown in the accompanying drawings shall be interpreted as illustrative and not in a limiting sense.

Having thus described my invention, what I claim as new and desire to secure by Letters Patent of the United States is:—

1. An operating gear for roller awnings including supporting brackets for the ends of an awning roller, a power transmitting roller-actuating gear train mounted in one of the brackets, and a hub fixed to the driven gear of the train and adapted to receive the open end of a tubular awning roller, and having a slot and pin connection with said hub, whereby the roller is coupled to the gear train as an incident of mounting the roller in its brackets.

2. In an awning operating mechanism, a bracket fixture adapted to be secured to a window frame, including an attaching portion and a bearing plate portion, a train of intermeshing driving gears mounted in said bearing plate portion, a hub fixed to turn with the driven gear of said train, adapted to receive and support the end of an awning roller and to couple said roller to the train, and a second hub fixed to turn with the driving gear of said train and adapted to receive and support the end of a driving shaft and to couple said shaft to the train.

3. In an awning operating gear, the combination with an awning roller adapted to be mounted on the outside of a window frame, of brackets removably supporting said roller, a roller operating gear train carried by one of said brackets, a driving shaft disposed parallel to and inwardly of the roller, said shaft being also supported at one end by said bracket.

4. In an awning operating gear, the combination with an awning roller adapted to be mounted on the outside of a window frame, of brackets removably supporting said roller, a roller operating gear train carried by one of said brackets, a driving shaft disposed parallel to and inwardly of the roller, said shaft being also supported at one end by said bracket, the means for supporting the shaft and roller from the bracket comprising hubs fixed to the driving and driven gears of the train and to which the ends of the shaft and roller are connected.

5. In an awning operating gear, the combination with an awning roller adapted to be mounted on the outside of a window frame, of brackets removably supporting said roller, a roller operating gear train carried by one of said brackets, a driving shaft disposed parallel to and inwardly of the roller, said shaft being also supported at one end by said bracket, the means for supporting the shaft and roller from the bracket comprising hubs fixed to the driving and driven gears of the train and to which the ends of the shaft and roller are connected, said hubs having slot

- and pin connections with the shaft and roller, whereby said members are positively coupled to turn with the gear train.
6. As a new article of manufacture, a bracket including an attaching plate portion and a pair of spaced parallel bearing plate portions, and a train of awning roller operating gears mounted between and borne by said parallel plate portions. 70
- 10 7. As a new article of manufacture, a bracket including an attaching plate portion and a pair of spaced parallel bearing plate portions, a train of awning roller operating gears mounted between and borne by said parallel plate portions, certain of said gears including projecting axles, hubs on said axles exteriorly of said plates and radial pins projecting from said hubs for the reception of hollow shafts or rollers having slotted ends. 75
- 15 8. In an awning operating mechanism, for use with a fixed type window sash, an awning operating rotary member adapted for disposition exteriorly of the sash, an endless sprocket chain including a run for disposition exteriorly of the sash and a run for disposition interiorly thereof and a plurality of guiding sprockets for the chain adapted to be disposed exteriorly and interiorly of the sash, one of said sprockets being fixed to the 80 rotary member. 90
- 20 9. In an awning operating mechanism, for use with a fixed type window sash, an awning operating rotary member adapted for disposition exteriorly of the sash, an endless sprocket chain including a run for disposition exteriorly of the sash and a run for disposition interiorly thereof and a plurality of guiding sprockets for the chain adapted to be disposed exteriorly and interiorly of the sash, one of said sprockets being fixed to the 85 rotary member. 95
- 25 10. In an awning operating mechanism, for use with a fixed type window sash, an awning operating rotary member adapted for disposition exteriorly of the sash, an endless sprocket chain including a run for disposition exteriorly of the sash and a run for disposition interiorly thereof and a plurality of guiding sprockets for the chain adapted to be disposed exteriorly and interiorly of the sash, one of said sprockets being fixed to the 90 rotary member, and a flexible sleeve member normally slidable on the interior run of the chain, adapted to be manually grasped to frictionally engage the chain for operating purposes. 100
- 30 11. An awning roller adapted to be detachably mounted at the exterior of the frame and to extend substantially the full width of the sash, a shaft operatively connected to the roller, disposed in substantial parallelism therewith and adapted to lie between the 105 roller and sash, an endless sprocket chain including a run for disposition inside of the sash and a run for disposition outside of the sash, said chain being operatively connected to said shaft. 110
- 35 12. A device for use with a window frame and sash of the fixed type having a vertical central bar, of an awning roller detachably mounted at the exterior of the frame and extending substantially the full width of the sash, a shaft operatively connected to the roller, disposed in substantial parallelism therewith and lying between the roller and sash, an endless sprocket chain including a run disposed inside of the sash and a run 115 disposed outside of the sash, said chain being operatively connected to said shaft, and running through said central vertical bar. 120
- 40 13. A device for use with a window frame and sash, of the fixed type having a central vertical bar comprising an awning roller to be detachably mounted at the exterior of the frame and to extend substantially the full width of the sash, a shaft operatively connected to the roller, disposed in substantial parallelism therewith and to lie between the roller and sash, an endless sprocket chain including a run adapted to be disposed inside of the sash and a run adapted to be disposed outside of the sash, said chain being operatively connected to said shaft, said chain running through the central bar, and said shaft extending from said bar to one side of the frame. 125
- 45 14. As a new article of manufacture, an operating device for endless sprocket chains or the like including a flexible sleeve, adapted to encircle the chain and including substantially rigid spool members at each end slidable freely on the chain, said sleeve adapted to be manually grasped and frictionally engaged with the chain, whereby the sleeve will serve as a protective handle. 130
- 50 15. A springless roller for awnings or the like including a metal tube, a gudgeon supporting plug fixed in one end of the tube, the other end of the tube being constructed to cooperatively provide a slot and pin connection with a hub member over which the end of the tube is adapted to be slipped and with which the tube is adapted to turn. 135
- 55 16. In an operating mechanism for roller awnings, the combination of a sash awning roller adapted to be disposed exteriorly of a sash, supporting brackets therefor and a flexible operating device, one of said brackets comprising a unitary structure embodying a substantially thin flat body portion and power transmitting mechanism to couple the roller and operating device. 140
- 60 17. In an operating mechanism for roller awnings, the combination of a sash awning roller adapted to be disposed exteriorly of a sash, supporting brackets therefor and a flexible operating device, one of said brackets 145

ets comprising a unitary structure embodying a substantially thin flat body portion and power transmitting mechanism to couple the roller and operating device, and a shaft operated by the flexible device supported at one end by said bracket and operatively connected to the power transmitting mechanism, the other end of the shaft being disposed adjacent the center of the sash through which the flexible device turns.

18. A device for use with a window frame and sash, of the fixed type having a central vertical bar comprising an awning roller detachably mounted at the exterior of the frame and extending substantially the full width of the sash, a shaft operatively connected to the roller, disposed in substantial parallelism therewith and lying between the roller and sash, an endless sprocket chain including a run disposed inside of the sash and a run disposed outside of the sash, said chain being operatively connected to said shaft, said sash including a central vertical bar through which the chain runs, said shaft extending from said bar to one side of the frame, and mounting at one end a sprocket wheel serving as the operative connection with the chain.

19. A device for use with a window frame and sash, of the fixed type having a central vertical bar comprising an awning roller detachably mounted at the exterior of the frame and extending substantially the full width of the sash, a shaft operatively connected to the roller, disposed in substantial parallelism therewith and lying between the roller and sash, an endless sprocket chain including a run disposed inside of the sash and a run disposed outside of the sash, said chain being operatively connected to said shaft, said sash including a central vertical bar through which the chain runs, said shaft extending from said bar to one side of the frame, and mounting at one end a sprocket wheel serving as the operative connection with the chain, and at its opposite end being indirectly connected with the roller.

20. In an awning operating mechanism for window sashes including a rotary member disposed exteriorly of the sash, an endless sprocket chain including a run disposed exteriorly of the sash and a run disposed interiorly thereof and a plurality of guiding sprockets for the chain disposed exteriorly and interiorly of the sash, one of said sprockets being fixed to the rotary member, a stationary frame piece through which the sprocket chain runs and behind which one run thereof is concealed.

21. As a new article of manufacture, an operating device for endless sprocket chains or the like including a flexible sleeve, adapted to encircle the chain and including substantially rigid spool members at each end slideable freely on the chain, said sleeve adapted

to be manually grasped and frictionally engaged with the chain, whereby the sleeve will serve as a protective handle, said sleeve including an inner lamination of tough flexible material and an outer lamination of soft flexible cushioning material.

22. In an operating mechanism for awnings; an awning roller adapted to be disposed exteriorly of the sash, supporting brackets therefor, a train of power transmitting gears mounted in one of the brackets, a sprocket chain for operating the gear train including a run adapted to be disposed exteriorly of the sash and a run adapted to be disposed interiorly thereof, said gear train including driving and driven gears and a reversing idler gear disposed between them.

Signed at New York, in the county of New York and State of New York, this 20th day of April, A. D. 1928.
